(57) **CLAIM**

The ornamental design for a curved bottle, as shown and described.

DESCRIPTION

FIG. 1 is a top, rear, and left side perspective view of the curved bottle;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a top, front, and right side perspective view thereof.
The broken lines showing structures associated with the curved bottle are for illustrative purposes only and form no part of the claimed design.
